UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT STOCK COMPANY OF FRANCE.

BARREL-CARRIAGE OF ORDNANCE.

1,280,559.

Specification of Letters Patent.

Patented Oct. 1, 1918.

Application filed May 15, 1917. Serial No. 168,855.

To all whom it may concern:

Be it known that I, EUGÈNE SCHNEIDER, a citizen of the French Republic, and residing at Le Creuzot, Saône-et-Loire, France, have 5 invented a new and useful Improvement in or Relating to the Barrel-Carriages of Ordnance, which is fully set forth in the following specification.

In the French Patent No. 463988 there is 10 described a carriage for dismounting a gun barrel and for transporting the same after it has been separated from its carriage, characterized by the feature that the axle of the rear carriage is adapted to receive directly the dismounted gun barrel, the said rear carriage comprising for this purpose a cradle-like structure.

The present invention has now for its object to provide an eminently practical improved construction of this cradle-like structure (hereafter termed "cradle") of the rear carriage.

The manner in which this invention is to be performed will now be more particularly 25 described with reference to the accompanying drawings which illustrate by way of example one form of the invention. In these drawings:

Figure 1 is an elevation of the rear carriage axle, partly in vertical section along the longitudinal center line of the axle; and

Fig. 2 is a vertical cross section, partly in elevation, on the line II-II of Fig. 1.

According to this invention, the half collar or cradle A, instead of being made in one piece with the axle B, is suspended elastically from said axle. For this purpose the cradle which constitutes an independent part of the axle, comprises two 35 under extensions A¹, A² of its inverted arch, two fork-like projections C C which straddle the axle B. Each of these forks carries between the lower parts of its limbs one of the abutments, such as a box D for a shock-absorbing device (metal springs or other

devices), while the other abutment is fixed to the axle.

In the example shown, the shock-absorbing devices consist of metal springs E E¹. The upper abutment supported by each of the forks C C, consists of the end d of the box D. The abutment carried by the axle consists of a washer F held by means of a nut f at an adjustable point along a bolt G that is screwed in a tapped hole in the axle 55 B and is fixed by a pin g.

In order to avoid a sudden shock between the axle and the end d of a box D due to the oscillation of the axle, a Belleville washer H is arranged around a shoulder on the bolt 60 G. All longitudinal movement of the axle relative to the cradle is prevented by stops b between which the limbs of the forks C are guided and held.

Having now described my invention, what I claim as new and desire to secure by Letters Patent is:

1. A rear gun carriage comprising a gun-supporting cradle having depending forked members, a wheeled axle provided with 70 vertical guides for receiving said forked members, depending suspension rods fast to said axle, and abutments fast to the lower ends of said forks and yieldingly supported by said suspension members.

2. A rear gun carriage as claimed in claim 1 wherein said abutments comprise spring barrels adapted to be secured to the lower ends of said forks and to receive said suspension rods in combination with springs 80 intermediate the upper ends of said barrels and the lower ends of said suspension rods.

In testimony whereof I have signed this specification in the presence of two subscribing witnesses.

EUGÈNE SCHNEIDER.
